UNITED STATES PATENT OFFICE.

HENRY F. STANLEY, OF NEW ORLEANS, LOUISIANA.

REFRIGERATOR-CAR.

SPECIFICATION forming part of Letters Patent No. 732,597, dated June 30, 1903.

Application filed October 6, 1902. Serial No. 126,168. (No model.)

To all whom it may concern:

Be it known that I, HENRY F. STANLEY, a citizen of the United States, and a resident of New Orleans, in the parish of Orleans and State of Louisiana, have invented a new and Improved Refrigerator-Car, of which the following is a full, clear, and exact description.

The present invention relates to freight-cars of the general construction shown in the United States patents granted to me April 19, 1898, No. 602,483, and November 6, 1900, No. 661,429. Said cars are specially designed for the carrying of fruits and other perishable goods, and to this end have hollow walls and means for thoroughly ventilating the car, as well as certain chambers for receiving ice, whereby the car may be refrigerated when this is required by the character of the freight.

The present invention provides a novel means for forming the ice-chambers, the partitions and racks that enter into the construction of this feature of the car being arranged to be readily folded into small compass and moved to a position enabling practically the whole content of the car to be utilized for freight when refrigeration is not required.

The invention will be hereinafter particularly described and then defined in the claims.

Reference is to be had to the accompanying drawings, forming a part of this specification, in which similar characters of reference indicate corresponding parts in all the views.

Figure 1 is a broken longitudinal sectional elevation of a car provided with my improved means for forming the ice-chamber, the said means being shown at the left of the figure arranged to receive ice and shown at the right of the figure in folded position, the section being indicated by the line 1 1 of Fig. 2. Fig. 2 is a fragmentary sectional plan view. Fig. 3 is a transverse sectional elevation, the section being indicated by the line 3 3 in Fig. 1. Fig. 4 is a detail view, on a larger scale, showing the joint in the articulated partition that forms a wall of an ice-chamber and certain devices employed to aid in sustaining said partition when not in use; and Fig. 5 is a detail view showing means for securing the bottom of the partition in either of its positions. The hollow walls A of the car, the floor B, and the ventilating means need not be particularly described herein, as the same are

fully disclosed in my previous patents mentioned above.

The improved means for forming the ice-chambers comprise two main parts consisting of an articulated partition C and racks D, forming the bottom of the chambers. There is one chamber at each end of the car, and for each chamber two partitions C and two racks D are preferably provided, adjacent sets extending from the opposite sides of the car to about the longitudinal center thereof, as seen in Figs. 2 and 3, the partitions being spaced from the adjacent end walls of the car the required distance to afford an ice-chamber of the desired capacity.

The partition C in the specific detail construction illustrated is made up of top and bottom bars c' c' and vertical slats c². I suspend the partitions from a beam E, extending transversely beneath the roof A', thus relieving the roof of strain. The beam E is spaced from the roof a sufficient distance to allow circulation of air around said beam. The connection between the partitions C and beam E is effected by clips e on said beam, extensions c³ on the partitions, and bolts e', passing through said clips and extensions, whereby the partitions may swing toward and from the end wall of the car. Each partition C is articulated to flex at its transverse center, being formed of upper and lower members jointed by hinges c⁴, secured on the outer face of the members. To hold the members in alignment as a rigid partition, bolts c⁵ are provided at the joint, being secured on one section to slide vertically and engage keepers c⁶ on the other section.

The ice - supports D, hereinafter called "racks," form the bottom of each ice-chamber and are hingedly connected at one end, as at d, to the inner face of the lower members of each partition a proper distance above the car-floor to allow necessary circulation of air. A beam or sill F extends across the car near each end, being spaced from the end wall and from the floor of the car, and the racks D when in the lowered position are supported on their inner ends on said beam. With this construction the racks D may be swung upward on their connections at d to lie against the inner faces of the partitions, and each partition-section may be swung on

its suspending device and flexed on its hinges c^4 to bring said racks and the lower members of the partition parallel with and close to the end wall of the car, so that the said partition members rest on the beam F, as seen at the right in Fig. 1, the upper members of the partition then ranging diagonally from the flexible joint to the described suspending devices connecting the partitions with the beam E.

- 10 The lower end of each partition carries bolts b^7 , which may enter holes b in the floor B when the partition is in the vertical position, (see Fig. 5,) and thus fasten the partition against movement. The said bolts b^7 15 when the partition rest on the beam F enter holes or recesses f in said beam, and in order to further fasten the partitions and racks in the folded position hooks H, Fig. 4, are secured to each end wall of the car and 20 are adapted to engage eyes c^8 on the partitions, as best shown in Fig. 4.

When the partitions and racks are set up for use, ice may be entered through inlets I, provided in the car-roof, as fully explained 25 in my Patent No. 661,429.

Having thus described my invention, I claim as new and desire to secure by Letters Patent—

1. The combination with a structure to be 30 refrigerated, of a swinging partition suspended in a position spaced from a wall of said structure and articulated to flex intermediate its ends and fold toward said wall, a rack hinged to said partition to be carried by the 35 said partition when the latter is swung in its suspending devices and flexed, and means for holding the partition in either the folded or unfolded position.

2. The combination with a structure to be 40 refrigerated, of a swinging partition suspended in a position spaced from a wall of said structure and articulated to flex intermediate its ends and fold toward said wall, a rack hinged to said partition, a support adjacent 45 said end wall for receiving the free end of the rack or the lower end of the partition, and means for holding the partition in either the folded or unfolded position.

3. The combination with a structure to be 50 refrigerated, of a swinging partition suspended in a position spaced from a wall of said structure and articulated to flex intermediate its ends and fold toward said wall, a rack hinged to said partition, a support adjacent 55 said end wall for receiving the free end of the rack or the lower end of the partition, said support being spaced from said wall and from the floor of the structure, and means for holding the partition in either the folded 60 or unfolded position.

4. The combination with a structure to be 65 refrigerated, of an overhead beam, a swinging partition suspended from said beam and articulated to flex intermediate its ends and fold toward the adjacent wall of the said structure, a rack hinged to said partition, a beam extending across the structure, adjac-

cent to the mentioned wall of the structure and spaced from said wall and from the floor of the structure, said beam and floor having 70 recesses, and bolts carried by the partition at the lower end for entering either of said recesses.

5. The combination with a structure to be refrigerated, of an overhead beam, spaced 75 from the roof of said structure, a swinging partition suspended from said beam and articulated to flex intermediate its ends and fold toward the adjacent wall of the said structure, a rack hinged to said partition, a beam extending across the structure, adjacent to the mentioned wall of the structure, spaced from said wall and from the floor of the structure, said beam and floor having recesses, bolts carried by the partition at the 80 lower end for entering either of said recesses, and means to prevent flexure of the partition when unfolded.

6. The combination with a structure to be refrigerated, of an overhead beam, a swinging 90 partition suspended from said beam and articulated to flex intermediate its ends and fold toward the adjacent wall of the said structure, a rack hinged to said partition, a beam extending across the structure, adjacent to the mentioned wall of the structure and spaced from said wall and from the floor of the structure, said beam and floor having recesses, bolts carried by the partition at the 95 lower end for entering either of said recesses, means to prevent flexure of the partition when in the unfolded position, an eye on the partition, and a hook on the adjacent wall of the structure, for engaging said eye.

7. The combination with a car, of a partition suspended to swing toward an end wall of the car and spaced from said wall, said partition consisting of two sections, each composed of two members hinged together on a horizontal line, the said sections extending from opposite sides of the car to about the center, a rack hinged to the lower member of each section on the inside or that side which is toward the said end wall, and means for holding the partition adjacent to said end 100 wall or spaced therefrom.

8. The combination with a structure to be refrigerated, of a swinging partition suspended in a position spaced from a wall of said structure, and articulated to flex intermediate its ends and fold toward said wall, a rack hinged to said partition near the lower end, on the side which faces said wall, and means for holding the partition and rack in either the folded or unfolded position, said means 115 including a rest for receiving the lower end of the partition in its folded position.

In testimony whereof I have signed my name to this specification in the presence of two subscribing witnesses.

HENRY F. STANLEY.
